DENTAL SYRINGE

John A. Maurer and Kenneth R. Lappin, Canton, Ohio,
assignors to The Weber Dental Manufacturing Company,
Canton, Ohio, a corporation of Ohio

Filed June 9, 1961, Ser. No. 65,535

Term of patent 14 years

(Cl. D24—1)

FIG. 1 is a side elevation of a dental syringe, showing our new design;

FIG. 2 is a fragmentary top plane view thereof with portions omitted for convenience of illustration; and

FIG. 3 is a left end elevation thereof.

We claim:

The ornamental design for a dental syringe, substantially as shown and described.
